UNITED STATES PATENT OFFICE.

J. LESTER OSGOOD, OF BUFFALO, NEW YORK, ASSIGNOR TO SAXTON & OSGOOD, OF SAME PLACE.

BIT-BRACE.

SPECIFICATION forming part of Letters Patent No. 361,368, dated April 19, 1887.

Application filed June 1, 1886. Serial No. 203,835. (No model.)

To all whom it may concern:

Be it known that I, J. LESTER OSGOOD, of the city of Buffalo, in the county of Erie and State of New York, have invented a new and 5 useful Improvement in Bit-Braces, of which the following is a specification.

This invention relates to an improvement in the construction of the bit-stock in which the bit is secured, and which is composed of two 10 clamping-jaws secured to a central socket portion and a screw-threaded sleeve, which surrounds the jaws and socket portion, whereby the jaws are clamped tightly against the bit.

The object of my invention is to improve 15 the construction of this class of bit-stocks and to render the same simple in construction and durable and convenient in use.

The invention consists of the improvements 20 which will be hereinafter fully described, and pointed out in the claims.

In the accompanying drawings, Figure 1 is a sectional elevation of a bit-stock provided 25 with my improvement. Fig. 2 is a section at right angles to Fig. 1, showing the socket portion in elevation. Fig. 3 is a cross-section in line xx , Fig. 1. Fig. 4 is a sectional elevation in line yy , Fig. 3. Fig. 5 is a perspective view of the upper end of the socket portion 30 with the clamping-jaws and screw-sleeve removed. Fig. 6 is a perspective view of the clamping-jaws. Fig. 7 is a sectional elevation of the socket portion, the section being taken through the recess between the posts.

Like letters of reference refer to like parts 35 in the several figures.

A represents the end of the brace, which is of any ordinary or suitable construction, and which carries the stock in which the bit is secured.

40 B represents the shank or socket piece formed at the end of the brace, and c the socket, of rectangular cross section, which is formed in the piece B and receives the shank of the bit. The shank B is provided with an external screw-thread.

45 d d are two posts formed on the end of the socket portion B and separated by a diametrical slot, d' .

E E represent the clamping-jaws, arranged 50 in the slot d' between the posts $d d$ and on opposite sides of the socket c. Each of the posts

d is provided on its inner side with a lug or projection, e, which engages in a groove or recess, f, formed in the adjacent side of the jaw E.

f' represents a groove or recess formed in 55 the opposite side of the jaws E, and e' a lip or projection formed on the end of each post d adjacent to the recess f'. Each post d is provided with a lug, e, on one side of the socket c, and a lip, e', on the opposite side of the socket, 60 so that the two opposite sides of both posts d d, on the same side of the socket, between which one of the jaws E is arranged, contain a lug, e, and a lip, e'. The grooves f extend from the inner faces or edges of the jaws outwardly, 65 and are closed at their outer ends, and the recesses f' extend from the outer edges of the jaws inwardly, and are closed at their inner ends, as shown in Fig. 6. The two recesses f are arranged on diagonally-opposite sides of 70 the jaws E, and the two lugs e are likewise arranged diagonally. The recesses f' and the lugs e' are arranged similarly, but on opposite sides of the jaws and posts.

Upon inserting the jaws E into the slot d' , 75 the lugs e enter the recesses f, and the lips e' will stand opposite the recesses f' in the adjacent sides of the jaws. When the jaws have been inserted in the slot d' , the lips e' are bent over, so as to enter the recesses f', as shown 80 in Figs. 2 and 4, whereby the jaws are held in the slot d' on opposite sides of the socket c.

g g are lugs or projections formed on the inner sides of the posts d on opposite sides of the socket c, between the lower ends of the jaws 85 and projecting into the slot d' , so as to prevent the inner or lower ends of the jaws from coming in contact with each other.

The jaws E are provided on their opposite sides or faces with V-shaped recesses, which 90 receive the shank of the bit.

H represents the screw-sleeve, which surrounds the socket portion B and engages with a screw-thread, i, formed thereon, so that by screwing the sleeve H down the outer contracted portion of the sleeve will close the 95 jaws E upon the bit and securely fasten the latter in the socket.

The lugs e and grooves f limit the inward movement of the jaws, and the lugs e' and 100 grooves f' limit the outward movement of the jaws. Both sets of lugs and grooves serve to

attach the jaws permanently to the socket B, and prevent the jaws from becoming detached when the screw-sleeve H is removed.

The socket portion B is readily cast of malleable iron with the lugs e and e', as shown in Fig. 5, and the jaws are also readily and cheaply constructed and attached to the socket by a cold-shut of the lugs e', the whole forming a compact, reliable, and durable fastening device for the bit.

In inserting the square shank of the bit into the socket, the inner narrow end of the shank enters the socket c and is held and properly centered thereby, while the outer portion of the shank is grasped by the jaws E, and the bit thereby firmly secured to the stock.

I claim as my invention—

1. The combination, with the socket portion B, carrying posts d d, which are separated by a transverse slot, d', and provided with lugs e', of jaws E, provided in their sides with grooves f", open at their outer ends and closed

at their inner ends, the lugs e' being bent to project into the grooves f" after the jaws E have been inserted in the slot d', whereby the outward movement of the jaws is limited and the jaws are permanently attached to the socket portion, substantially as set forth.

2. The combination, with the socket portion B, carrying posts d, which are separated by a transverse slot, d', and provided with lugs e and e', of jaws E, provided in their sides with grooves f, open at their inner ends and closed at their outer ends, in which the lugs e engage, and also with grooves f', open at their outer ends and closed at their inner ends, in which the lugs e' engage, substantially as set forth.

Witness my hand this 14th day of May, 1886.

J. LESTER OSGOOD.
